UNITED STATES PATENT OFFICE.

CHRISTIAN OLSEN, OF JOPLIN, MISSOURI.

WHEEL-HUB.

SPECIFICATION forming part of Letters Patent No. 242,683, dated June 7, 1881.

Application filed March 7, 1881. (No model.)

To all whom it may concern:

Be it known that I, CHRISTIAN OLSEN, a citizen of the United States, resident at Joplin, in the county of Jasper and State of Missouri, have invented certain new and useful Improvements in Lock-Spoke Wheel-Hubs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a representation of a vertical section, and Fig. 2 is a detail view.

This invention relates to improvements in wheels, more especially to the construction of the spoke-tenons and mortises in the hub to receive them. Its object is the production of a wheel the spokes of which will not jump out of the hub.

The invention consists of a hub having the shaped mortises hereinafter described, in combination with spokes having tenons to be inserted in said mortises, all as set forth, and particularly pointed out in the claim.

In the annexed drawings, A is one of the spokes, having tenon B beyond the shoulders *a a*. One face, *b*, of this tenon runs down perpendicular at *z*, then turns in obliquely at *y*, and down perpendicular at *x* to the point *v*. The other face, *b'*, runs down perpendicular at *z'*, parallel to *z*, then turns out obliquely at *y'* at a different angle from *y*, and runs in on a bevel at *x'* to the point *v*. This forms a tenon straight at the shoulders, having an angle at the middle, and a lower portion whose edges form an angle.

The hub C, which is made solid, has mortises *c*, similar in shape to the upper and middle portions of the tenons, made circumferen-

tially therein at its middle. The partitions which separate these mortises *c* stop short of the center of the hub, as shown. The spokes 45 are driven with their tenons into these mortises. The tenons rest with their upper and middle portions in the mortises, their lower portions coming together at the center, the bend of one fitting snugly against the perpendicular face of the other. It will thus be seen that one of the oblique shoulders of one spoke comes in under that of its next neighbor, and thus any tendency to jump one spoke is resisted by the next, and the transferred strain 55 on this by the next, so that the shoulders form an interlocked chain around the hub.

The tenon of a spoke has been made alternately concavo-convex or serpentine, so that the bold or bearings of the two sides have 60 been diagonally rather than transversely opposite to each other; but in that instance the inner ends of the tenons did not come in contact, as in my case, and that shape is not claimed herein; besides, the partitions between 65 the mortises extended to the bore of the hub.

I claim—

A spoke the tenon of which has a straight upper portion, oblique middle, and a lower portion, the faces of which form an angle, in 70 combination with a hub the mortises of which have a shape to suit the upper and middle portions of the tenon, and run together, so that the spokes project through the mortises and have a solid bearing against each other at their 75 lower ends, substantially as and for the purposes set forth.

In testimony whereof I affix my signature in presence of two witnesses.

CHRISTIAN OLSEN.
